UNITED STATES PATENT OFFICE.

CHARLES F. WALTERS, OF PROSPECT, NEW YORK.

DESIGN FOR A CAMPAIGN-LANTERN.

SPECIFICATION forming part of Design No. 32,992, dated July 24, 1900.

Application filed June 7, 1900. Serial No. 19,468. Term of patent 3½ years.

To all whom it may concern:

Be it known that I, CHARLES F. WALTERS, a citizen of the United States, residing at Prospect, in the county of Oneida and State of New York, have invented a new and original Design for a Campaign-Lantern, of which the following is a specification.

This invention relates to a new and original design for campaign-lanterns; and the essential feature resides in a rectangular body with a cover reduced toward its top portion and supplied with a circular cap, the body, cover, and cap being provided with a plurality of apertures with outwardly-struck portions therearound.

The figure of the drawing represents a perspective view of the lantern embodying the features of the design.

The numeral 1 designates a rectangular body having panels 2 in the opposite ends,

outstruck vertical corners 3, and upper surrounding corrugations and ribs 4. On the body 1 is applied a cover 5, which is reduced toward its top portion, as at 6, and in the center thereof is a circular cap 7. The body, 25 cover, and cap have a plurality of openings 8 therein with outstruck portions around the same, which give to the entire device an ornamental appearance.

Having thus described the invention, what 30 is claimed as new is—

The design for a campaign-lantern, herein shown and described.

In testimony that I claim the foregoing as my own I have hereto affixed my signature in 35 the presence of two witnesses.

CHARLES F. WALTERS.
